(57) **CLAIM**

The ornamental design for a table, as shown and described.

DESCRIPTION

FIG. 1 is a perspective view of a table showing my new design;

FIG. 2 is a side elevational view, the opposite side being a mirror image thereof;

FIG. 3 is an end elevational view, the opposite end being a mirror image thereof; and,

FIG. 4 is a top view thereof.

The views of the table not shown form no part of the claimed design. The shading shown on the table top surface of FIGS. 1 and 4 indicate a planar surface. The separation and bracket indicate, for ease of illustration, that the precise length of the table is not claimed.
